FIG. 2B

FIG. 5

FIG. 7

1 PACKAGE

FIELD OF THE INVENTION

The present invention relates to packages for holding consumer products and more particularly, to packages to facilitate the dispensing of cartridges.

BACKGROUND OF THE INVENTION

More consumers are starting to prefer shopping online and receiving product in the mail rather than going to stores to make purchases in person. Accordingly, manufacturers have been providing direct to consumer (DTC) packages to ship their products safely and economically to consumers. Another consumer trend is sustainability. Consumers prefer products and packages that are more sustainable, have less waste and a smaller environmental impact. The cost of shipping products through the mail system is typically absorbed by the manufacturer. Accordingly, manufacturers need to minimize costs as much as possible to maintain margins that are similar to selling the same product in a store. It typically costs more to ship products in boxes than envelopes. However, shipping products in envelopes requires the product being shipped must be below a certain thickness and meet flexibility requirements. For example, the United States Postal Office requires that when a product is placed in the standard shipping envelope, the envelope must be flexible along the two axes of the envelope in order for the envelope to be successfully processed by the current sorting equipment. It is also preferred to send more products within an envelope to decrease overall shipping costs. However, shifting of the products within the envelope may negatively impact the flexibility of the envelope depending on the location of the products within the envelope.

More packages are being designed for direct to consumer product offerings. However, consumers desire the same ease of use and functionality of products and packages that are sold in stores. Despite the use of known packaging techniques, there remains a need to further modify consumer product packages to provide a package that allows manufacturers to ship products to consumers in a reliable, economically and efficient manner without negatively impacting the consumer experience.

SUMMARY OF THE INVENTION

In one aspect, the invention features, in general, a package with a first container defining a storage region defined by side walls extending upward from a lower region to a top surface. A first cartridge is positioned within the storage region of the first container. A card is mounted to the top surface of the first container. A leading edge of the card and a front face of the first container define an opening dimensioned to receive a handle.

In another aspect, the invention features, in general, a package having a first container defining a storage region defined by side walls extending upward from a lower region to a top surface. A first cartridge positioned within the storage region of the first container. A card mounted to the top surface of the first container. The card defines a cartridge opening having a length that is less than a length of the first cartridge. The card has at least one perforated segment extending inwardly from the opening.

BRIEF DESCRIPTION OF THE DRAWINGS

FIG. 1 is an assembly view of one possible embodiment of a package.

2

FIG. 2A is a front, bottom perspective view of the package of FIG. 1.

FIG. 2B is a rear, bottom perspective view of the package of FIG. 1.

FIG. 3 is a top perspective view of a portion of the package of FIG. 1.

FIG. 4 is a top perspective view of a handle being inserted in the package of FIG. 3.

FIG. 5 is a top perspective view of the handle removing a product from the container of FIG. 3.

FIG. 6 is an assembly view of a product mailer.

FIG. 7 is a bottom view of two of the packages of FIG. 2A connected.

DETAILED DESCRIPTION OF THE INVENTION

Referring to FIG. 1, an assembly view of one possible embodiment of a package 10 is shown. The package 10 may include a card 12 (e.g., a first card) and one or more containers 14, 16, 18 and 20 mounted to a bottom surface 22 of the card 12. The card 12 and/or the containers 14, 16, 18, and 20 may comprise one or more plant based materials, such as paperboard or bamboo. One or more products 24, 26, 28 and 30 may be positioned within a storage region 32, 34, 36 and 38 of the respective containers 14, 16, 18 and 20. Although the products 24, 26, 28 and 30 illustrated in FIG. 1 are cartridges for (e.g., for shaving), it is understood that other consumer products may be used, such as tooth brushes. Each of the storage regions 32, 34, 36 and 38 may be defined by respective side walls 40, 42, 44 and 46 extending upward from a lower region 48, 50, 52 and 54 to a top surface, such as a flange 56, 58, 60 and 62. The card 12 may be mounted to the flanges 56, 58, 60 and 62. In certain embodiments, the plurality of the containers 14, 16, 18 and 20 may be mounted and/or secured to the bottom surface 22, for example, with adhesive or other conventional methods known to those skilled in the art.

The card 12 may have a leading edge 64 and an opposing trailing edge 66. The leading edge 64 may be opposite and parallel to the trailing edge 66. The card 12 may have a first pair of perforated segments 68 and 70 and a second pair of perforated segments 72 and 74 extending inward from the leading edge 64. In certain embodiments, the first pair of perforated segments 68 and 70 and the second pair of perforated segments 72 and 74 may extend to a respective crease line 76 and 78. The leading edge 64 may have one or more curved regions 80 and 82 associated with the containers 14 and 18, respectively. The perforated segments 68 and 70 may extend from the curved region 80 and the perforated segments 72 and 74 extend from the curved region 82. In certain embodiments, the first pair of perforated line segments 68 and 70 may extend from the curved region 80 to the crease line 76. Similarly, the second pair of perforated line segments 72 and 74 (associated with the container 18) may extend from the curved region 82 to the crease line 78. In certain embodiments, the crease lines 76 and 78 may extend in a direction generally parallel to the leading edge 64 and/or the curved regions 80 and 82.

The card 12 may have a first pair of perforated segments 84 and 86 and a second pair of perforated segments 88 and 90 extending inward from the trailing edge 66. In certain embodiments, the first pair of perforated segments 84 and 86 and the second pair of perforated segments 88 and 90 may extend to a respective crease line 92 and 94. The trailing edge 66 may have one or more curved regions 96 and 98 from which the respective perforated segments 84, 86, 88

and 90 extend. For example, the first pair of perforated line segments 84 and 86 may extend from the curved region 96 to the crease line 92. Similarly, the second pair of perforated line segments 88 and 90 may extend from the curved region 98 to the crease line 84. In certain embodiments, the crease lines 92 and 94 may extend in a direction generally parallel to the trailing edge 66 and/or the curved regions 96 and 98.

The card 12 may have one or more perforated tabs 100, 102, 104 and 106 associated with one of the containers 14, 16, 18 and 20 to facilitate removal of the respective products 24, 26, 28 and 30 from the package 10. For example, the tearing of the perforated line segments 68 and 70 by lifting the perforated tab 100 (e.g., first perforated tab) may facilitate access and removal of the product 24 from the package 10. The first perforated tab 100 may be defined by the crease line 76 and the perforated line segments 68 and 70. The crease line 76 may facilitate keeping the perforated tab 100 in an open position, thus providing improved access and removal of the product 24. The curved region 80 may provide more intuitive identification and lifting of the tab 100.

The container 16 (e.g., second container) may be aligned with perforated tab 102 (e.g., second perforated tab). Accordingly, the tearing of the perforated line segments 84 and 86 by lifting the perforated tab 102 may facilitate access and removal of the product 26 from the package 10. The perforated tab 102 may be defined by the crease line 92 and the perforated line segments 84 and 86. The crease line 92 may facilitate keeping the perforated tab 102 in an open position, thus providing improved access and removal of the product 26. The curved region 96 may provide for more intuitive identification and lifting of tab 102.

The container 18 (e.g., third container) may be aligned with perforated tab 104 (e.g., third perforated tab). Accordingly, the tearing of the perforated line segments 72 and 74 by lifting the perforated tab 104 may facilitate access and removal of the product 28 from the package 10. The perforated tab 104 may be defined by the crease line 78 and the perforated line segments 72 and 74. The crease line 78 may facilitate keeping the perforated tab 104 in an open position, thus providing improved access and removal of the product 28. The curved region 82 may more intuitive identification and lifting of the tab 104.

The container 20 (e.g., fourth container) may be with the perforated tab 106 (e.g., fourth perforated tab). Accordingly, the tearing of the perforated line segments 88 and 90 by lifting the perforated tab 106 may facilitate access and removal of the product 30 from the package 10. The perforated tab 106 may be defined by the crease line 94 and the perforated line segments 88 and 90. The crease line 94 may facilitate keeping the perforated tab 106 in an open position, thus providing improved access and removal of the product 30. The curved region 98 may more intuitive identification and lifting of tab 106.

Referring to FIGS. 2A and 2B, a bottom perspective views of the package 10 is illustrated. In certain embodiments, the card 12 may include four quadrants 15a, 15b, 15c and 15d. One of the containers 14, 16, 18, and 20 may be positioned in each of the quadrants 15a, 15b, 15c and 15d. The containers 14, 16, 18 and 20 may extend from the bottom surface 22 of the card 12. The card 12 may have a slit line 108, 110, 112, and 114 extending around the respective containers 14, 16, 18 and 20 to facilitate the separation of the various containers 14, 16, 18 and 20. The slit line 108 may extend from the leading edge 64 to a first outer edge 120 transverse to the leading edge 64. The slit line 110 may extend from the trailing edge 66 to the first

outer edge 120. The slit line 116 may extend from the leading edge 64 to a second outer edge 122. The first outer edge 120 may be parallel to the second outer edge 122. The slit line 118 may extend from the second outer edge 122 to the trailing edge 66. The slit lines 108, 110, 112, and 114 may divide the card into the respective quadrants 15a, 15b, 15c and 15d.

As shown in FIG. 2A, the side walls 42 of the container 16 may include a front face 124 that defines an opening 126 extending into the storage region 34. The side walls 46 of the container 20 may include a front face 128 that defines an opening 130 extending into the storage region 34. The openings 126 and 130 may face in the same direction and may be defined by a portion of the trailing edge 66 (e.g., the curved regions 96 and 98). The front faces 124 and 128 may have a respective arcuate edge 132 and 134 to allow for improved access and removal of the products 26 and 30 from the containers 16 and 20. The openings 126 and 130 may extend in a direction generally parallel to the card 12. The openings 126 and 130 may face in the same direction (e.g., same direction as the trailing edge 66). The openings 126 and 130 facing outward and at the trailing edge 66 may facilitate the insertion of a handle (not shown) into the openings 126 and 130 because the openings 126 and 130 are not obstructed by another structure.

As shown in FIG. 2B, the side walls 40 of the container 14 may include a front face 136 that defines an opening 138 extending into the storage region 32. The side walls 44 of the container 18 may include a front face 140 that defines an opening 142 extending into the storage region 36. The openings 138 and 142 may extend in a direction generally parallel to the card 12. The openings 138 and 142 may face in the same direction (e.g., same direction as the leading edge 64). The openings 138 and 142 facing outward and positioned at the leading edge 64 may facilitate the insertion of a handle (not shown) into the openings 138 142 because the openings 138 and 142 are not obstructed by another structure. Accordingly, the openings 138 and 142 may face in an opposite direction of the openings 126 and 130 (FIG. 2A). The openings 138 and 142 may be defined by a portion of the leading edge 64 (e.g., the curved regions 80 and 82). The front faces 136 and 140 may have a respective arcuate edge 144 and 146 to allow for improved access and removal of the products 24 and 28 from the containers 14 and 18. The openings 138 and 142 may extend in a direction generally parallel to the card 12 (e.g., not into or through the card 12). Although the card 12 illustrated in FIGS. 2A and 2B is rectangular shaped, it is understood the card 12 may have other geometries to facilitate the positioning of the openings 126, 130, 138 and 142 all facing in an outer direction to facilitate insertion of a handle (not shown). For example, the card 12 may have a circular shape with openings facing outward.

FIGS. 3-5 illustrate the removal of one of the products 24, 26, 28 and 30 from the respective containers 14, 16, 18 and 20 shown in FIG. 1. It is understood that the package 10, may include the card 12 with multiple containers 14, 16, 18 and 20 (as shown in FIG. 1) or the card 12 having a portion removed with a single container (as shown in FIGS. 3-5). For example, the package 10 shown in FIGS. 3-5 may represent a portion of the card 12 having been separated along the slit line 108 (FIG. 2A). The opening 138 defined by the front face 136 may have a length "L1" that prevents the product 24 from inadvertently falling out of the container 14. However, the opening 138 may be dimensioned to receive a handle 148 (FIG. 4). The handle 148 may be able to connect to the product 24 through the opening 138. The handle 148

may extend generally parallel to the card 12 during insertion. The perforated segments 68 and 70 may facilitate separating the tab 100 from a portion of the card 12. For example, the tab 100 may be peeled back towards the crease line 76, tearing the card 12 along the perforated segments 68 and 70, as shown in FIG. 5. A length "L2" between the pair of perforated line segments 68 and 70 may define a cartridge opening 145 that may be greater than or equal to a length "L3" of the product 24, thus allowing the product 25 to be removed from the storage region 32 of the container 14 (e.g., via the cartridge opening 145 created by the lifting of the tab 100). Accordingly, the product 24 cannot be removed through the opening 138, but may be removed through the cartridge opening 145 created by the tab 100.

Referring to FIG. 6, one possible embodiment of the present invention is shown illustrating an assembly view of a product mailer 150. The product mailer 150 may include a shipping envelope 152 defining a pocket 154 configured to receive one or more of the packages 10 (e.g., a first package 10a and a second package 10b), as previously described. For example, FIG. 6 illustrates two of the packages 10a and 10b placed in the envelope 152; however it is understood only one of the packages 10a and 10b may be placed in the envelope 152 or more packages 10a and 10b may be placed within a larger envelope. It is understood that the first and second packages 10a and 10b are structurally the same as the package 10 previously described, accordingly, the same numerical numbers will be used to describe the first and second packages 10 and 10b. The first package 10a may include a first card 12a and the second package 10b may include a second card 12b. The first card 12a may have a bottom surface 22a. A plurality of containers 14a (hidden from view), 16a, 18a and 20a may extend from the bottom surface 22a of the first card 12a. The second card 12b may have a similar configuration as the first card 12a. For example, the second card 12b may have a bottom surface 22b. The bottom surface 22b of the second card 12b may face the bottom surface 22a of the first card 12a. A plurality of containers 14b, 16b, 18b and 20b may extend from the bottom surface 22b of the second card 12b.

The containers 18a and 20a of the first card 12a may be offset from the containers 14b and 16b of the second card 12b to facilitate compact stacking of the packages 12a and 12b. In certain embodiments, one or more of the containers 14b and 16b of the second card 12b may contact the bottom surface 22a of the first card 10a. In a similar fashion, one or more of the containers 18a and 20a of the first card 12a may contact the bottom surface 22b of the second card 12b. The offset configuration of the containers 14b and 16b of the second card 10b with the containers 18a and 20a of the first card 10a may provide for efficient usage of space within the pocket 154 of the envelope 152, as well as allow the envelope 152 sufficient flexibility during processing by equipment used for sorting envelopes and packages.

Referring to FIG. 7, a bottom view of the first card 12a and the second card 12b is illustrated. In certain embodiments, the first card 12a may be interconnected to the second card 12b by one or more bridges 156 and 158. The bridges 156 and 158 may extend from the first outer edge 120a of the first card 12a to the second outer edge 122b of the second card 12b. The bridges 156 and 158 may be formed as part of the first card 12a and the second card 12b as a unitary member. The bridges 156 and 158 spaced apart by a gap 160 to provide sufficient flexibility to facilitate the first card 12a and the second card 12b to fold over each other, thus allowing the first card 12a and the second card 12b to fit within the envelope 152, as shown in FIG. 6. The containers

14a and 16a may be spaced apart and the containers 18a and 20b may be spaced apart to define a gap 162a extending along the bottom surface 22a. The gap 162a may be dimensioned to receive two containers 16b and 20b of the second card 12b (e.g., the containers 16b and 20b may be positioned on gap 162a of the bottom surface 22a of the first card 12a when the second card 12b is folded on top of the first card 12a). Similarly, the second card 12b may have a gap 162b defined by the spacing apart of the containers 14b from 16b and 18b from 20b. The containers 14a, 16a, 18a and 20a of the first card 12a may be spaced apart to define a second gap 164a that extends in a transverse direction to the gap 162a. Similarly, the containers 14a, 16a, 18a and 20a of the second card 12b may be spaced apart to define a second gap 164b that extends in a transverse direction to the gap 162a. The gaps 162a, 162b, 164a and 164b may provide flexibility along two axis of the first and second packages 10a and 10b, thus facilitating proper handling and sorting by a shipping company (e.g., United States Post Office) when they are inserted into the envelope 152.

The dimensions and values disclosed herein are not to be understood as being strictly limited to the exact numerical values recited. Instead, unless otherwise specified, each such dimension is intended to mean both the recited value and a functionally equivalent range surrounding that value. For example, a dimension disclosed as "40 mm" is intended to mean "about 40 mm" Furthermore, dimensions should not be held to an impossibly high standard of metaphysical identity that does not allow for discrepancies due to typical manufacturing tolerances. Therefore, the term "about" should be interpreted as being within typical manufacturing tolerances.

Every document cited herein, including any cross referenced or related patent or application is hereby incorporated herein by reference in its entirety unless expressly excluded or otherwise limited. The citation of any document is not an admission that it is prior art with respect to any invention disclosed or claimed herein or that it alone, or in any combination with any other reference or references, teaches, suggests or discloses any such invention. Further, to the extent that any meaning or definition of a term in this document conflicts with any meaning or definition of the same term in a document incorporated by reference, the meaning or definition assigned to that term in this document shall govern.

While particular embodiments of the present invention have been illustrated and described, it would be obvious to those skilled in the art that various other changes and modifications can be made without departing from the spirit and scope of the invention. It is therefore intended to cover in the appended claims all such changes and modifications that are within the scope of this invention.

What is claimed is:

1. A package comprising:
a first container defining a storage region defined by side walls extending upward from a lower region to a top surface;
a first cartridge positioned within the storage region of the first container;
a card mounted to the top surface of the first container;
wherein a leading edge of the card and a front face of the first container define an opening dimensioned to receive a handle.
2. The package of claim 1 wherein the card comprises a pair of perforated segments extending inward from the leading edge of the card.

3. The package of claim 2 wherein the perforated segments extend to a fold line that extends parallel to the leading edge of the card.
4. The package of claim 1 wherein the card comprises a plant based material.
5. The package of claim 4 wherein the first container comprises a plant based material.
6. The package of claim 1 wherein the top surface of the first container comprises a flange that is sealed to the card.
- 10 7. The package of claim 1 wherein a length of the opening is less than a length of the cartridge.
8. The package of claim 2 wherein a distance between the pair of perforated segments is greater than or equal to a length of the cartridge.
- 15 9. The package of claim 8 wherein a length of the opening is less than a length of the cartridge.
10. The package of claim 1 wherein the leading edge has a curved region associated with the first container.
11. The package of claim 1 wherein the card comprises a slit line extending around the first container.
- 20 12. The package of claim 1 further comprising a second cartridge and a second container defining a storage region defined by side walls extending upward from a lower region to a top surface, wherein the second cartridge is positioned within the second container and the card is mounted to the top surface of the second container.
- 25 13. The package of claim 12 further wherein the card comprises a slit line extending around the second container.

14. A package comprising:
a first container having a front face that defines an opening extending into a storage region defined by side walls extending upward from a lower region to a top surface;
a first cartridge positioned within the storage region of the first container;
- a card mounted to the top surface of the first container, wherein a leading edge of the card and a front face of the first container define a cartridge opening dimensioned to receive a handle and having a length that is less than a length of the first cartridge,
wherein the card has at least one perforated segment extending inwardly from the opening.
15. The package of claim 14 further comprising a plurality of perforated segments extending inwardly from the opening to a crease line.
16. The package of claim 15 wherein the opening is dimensioned to receive a portion of a handle.
17. The package of claim 14 further comprising a slit line extending around the first container.
18. The package of claim 17 wherein the slit line extending around the first container extends from a first outer edge of the card to a second outer edge of the card that is transverse to the first edge.
19. The package of claim 14 wherein the card has a leading edge with a curved region associated with the first container.
20. The package of claim 19 wherein the at least one perforated line segments comprises a pair of perforated line segments that extend from the curved region.
